(57) **CLAIM**

The ornamental design for a chair, as shown and described.

DESCRIPTION

FIG. 1 is a perspective view of a chair showing my new design;

FIG. 2 is a front view thereof;

FIG. 3 is a rear view thereof;

FIG. 4 is a left side view thereof; the undisclosed right side view being a mirror image thereof;

FIG. 5 is a top view thereof;

FIG. 6 is a bottom view thereof; and,

FIG. 7 is a perspective view thereof with a seat part in use;

FIG. 8 is a perspective view thereof in an alternate folded configuration; and,

FIG. 9 is a perspective view thereof in the alternate folded configuration wrapped with the seat part.

The broken lines of the seat part in FIGS. 7 and 9 are for the purpose of illustrating the environmental structure and form no part of the claimed design.

The broken lines in FIG. 6 illustrate portions of the chair that form no part of the claimed design.

1 Claim, 9 Drawing Sheets
